Howard S. Smith,
His ATTORNEY

UNITED STATES PATENT OFFICE.

OLIVER W. WHITEHEAD, OF NEAR DAYTON, OHIO.

SASH-LIFTING DEVICE FOR AUTOMOBILES.

1,390,003.

Specification of Letters Patent. Patented Sept. 6, 1921.

Application filed October 25, 1920. Serial No. 419,339.

To all whom it may concern:

Be it known that I, OLIVER W. WHITEHEAD, a citizen of the United States, residing in the county of Montgomery, near the 5 city of Dayton, State of Ohio, have invented certain new and useful Improvements in Sash-Lifting Devices for Automobiles, of which the following is a specification.

The principal object of my invention is to 10 provide for automobiles and other vehicles, a sash lifting device which is simple in construction and efficient in operation. At present it requires a great deal of effort to raise and lower a window in a car by 15 straps, and in cases where the window sticks in the frame, the sash must be jarred loose by frequent blows with the hand or other object, resulting often times in damage to 20 the window construction and inconvenience to the passenger.

My improved lifting device obviates the above difficulties, inasmuch as the sash is raised and lowered by a screw that is operated by a handle within easy access of the 25 passenger. Means are also provided for automatically positioning the lower end of the sash on the fence iron after the raising operation, and for automatically releasing it from the latter at the beginning of the 30 lowering operation.

In the accompanying drawings, Figure 1 is a perspective view of the interior of a sedan, showing my improved sash raising and lowering device. Fig. 2 is a side view 35 of a window frame, showing the window as it has been partially raised by my improved lifting device. Fig. 3 is a front elevational view of the lifting device, showing the means for turning the worm. Fig. 4 is a 40 longitudinal sectional view taken through a door frame, showing my improved sash lifting means. Fig. 5 is a side elevational view of the worm and roller. Fig. 6 is a front elevational view of the same. Fig. 7 is a top plan view thereof, showing the stabilizing flange and shifting boss. Fig. 8 is a side elevational view of my sash lifting 45 means, showing how the roller is forced outwardly by the boss to lock the rails. Fig. 9 is a top plan view of the device, showing how the boss has forced the roller and bottom rail of the sash outwardly. And Fig. 50 10 is a top plan view of the device, showing the roller in its normal position within the worm.

Throughout the specification and drawings, similar reference characters denote corresponding parts.

In a detailed description of the preferred form of embodiment of my invention, the 60 numeral 1 designates an automobile of the sedan type containing a number of rectangular frames 2 in which windows 3 are vertically movable. Each window 3 is carried by a sash 4 having a transverse bottom rail 5. 65

Pivots secured in the middle top portion of the base rail 6 of the frame 2, is a vertically disposed worm 7 preferably of the cork screw type. The upper reduced end of this worm loosely projects through a tongue 70 piece 8 on a bracket 9 secured within a recess 10 provided in the rear middle portion of a transverse member 11 secured within the central portion of the frame 2. (See Figs. 2 and 3.)

For the purpose of rotating the worm 7, the following means are provided. Fast on the upper end of the worm 7 below the tongue piece 8, is a horizontally disposed bevel gear 12 that meshes with a vertically 80 disposed bevel gear 13 fast on a shaft 14 that is journaled in a bearing plate 15 secured to the outer middle portion of the transverse member or rail 11. Secured to the outer end of the shaft 14 is a handle 16 which, when 85 rotated by a passenger of the car, will turn the worm 7 to raise or lower the window sash 4 through the following means. (See Figs. 2 and 3.)

Suitably secured in a recessed portion of 90 the lower sash rail 5, is a metallic member 17 from which there projects outwardly a stud 18 on which a roller 19 is loosely mounted. On the outer end of this roller there is an integral flange 20 for a purpose hereinafter 95 to be described. (See Figs. 5 and 6.)

The worm 7 is preferably formed by spirally winding a strip of metal of greater width than thickness around a core rod, and then withdrawing the rod, leaving a worm 100 coil with a spiral space adapted to receive the roller 19, whose flange 20, being wider than that space, travels inside the coil to prevent the roller from being pulled out of that space. Therefore, when the worm 7 is 105 turned by the handle 16, the roller 19 will be raised or lowered by the spiral coil of which the worm consists, to raise or lower the window sash 4 to whose bottom rail 5 the support for said roller is secured. 110

In order to prevent a side wobble or the roller 19, and to insure it a true vertical movement, there projects outwardly from each side of the metallic member 17, a curved 5 flange 21 of greater width than the spiral slot in the worm that receives the roller 19. These flanges 21, 21 form together a yoke which freely slides along the outer surface of the worm 7 during the upward and down- 10 ward movement of the roller 19, to guide the latter and prevent any side friction of the sash. (See Figs. 7, 9 and 10.)

Mounted in the frame 2 opposite the trans- 15 verse member 11, is a lock board 22 between which and the member 11 space is left for a horizontal movement of the bottom rail 5 of the sash, toward the lock board. Secured to the inner surface of the lock board 22, and projecting a short distance above its top inner edge, is a fence iron 23 over which a pair of flanged pieces 24, 24 secured to the bottom rail 5 of the sash, are adapted to fit. For the purpose of shifting the bottom rail 5 of the sash so that these flanged pieces 20 24, 24 may be automatically hooked over the fence iron 23, to firmly hold the window in its uppermost position, and for automatically withdrawing said flanged pieces from said fence iron to permit the sash to be 30 lowered, the following means are provided.

Referring to Figs. 7 and 9, there projects inwardly from one of the flanges 21, at one side of the roller 19, a beveled boss 25. The latter is so disposed as to travel ahead of the 35 roller 19 in the spiral slot of the worm 7. At the upper end of the worm, the spiral slot terminates in an enlarged recess 26, the end of said slot being curved almost to circular form as shown in Fig. 3 to release the flange 40 20 on the roller 19. Now when the boss 25 is engaged by the upper curved wall of the enlarged recess 26 of the worm slot, it will force the roller 19 outwardly through said recess, since the latter is wider than the 45 flange on the roller. The metallic member 17, which carries the boss 25, will thereupon draw the bottom rail 5 of the sash a sufficient distance toward the lock board 22 to permit the flanged pieces 24, 24 to descend over 50 the fence iron 23 on the lock board, thereby to hold the sash 4 firmly in its raised position. (See Figs. 8, 9 and 10.)

Now, when it is desired to lower the sash, the handle 16 is turned in the opposite direction, whereupon the circular edge of the metal strip at the bottom of the enlarged recess 26, will engage the roller 19 to lift it, and through it, the bottom rail 5 of the sash will be raised a sufficient distance to lift the 60 flanged pieces 24, 24 above the fence rail 23 on the lock board 22. When the worm 7 is further turned by the handle 16, the flange 20 on the roller 19 will be drawn behind the spiral slot in the worm, to pull the rail 5 of 65 the sash inwardly a sufficient distance to

cause the flanged pieces 24, 24 to clear the fence iron 23, whereupon a further rotary movement of the worm 7 will draw the roller 19 downwardly to lower the sash. (See Figs. 3 and 10.)

It is thus seen that after the sash reaches the limit of its upward movement, its bottom rail 5 will be automatically secured to the fence iron on the lock board, and that at the beginning of the lowering operation of 75 the sash, the latter is automatically released from said fence rail.

A vertical slot 27 is provided in the upper end of the worm 7 through which the roller 19 may be pulled out without disturbing the worm when it is desired to remove the sash from the frame. (See Fig. 3.)

I do not wish to be limited to the details of construction and arrangement herein shown and described, and any changes or 85 modifications may be made therein within the scope of the subjoined claims.

Having described my invention, I claim:

1. In a device of the type described, the combination with a frame, of a sash vertically movable in said frame, a spirally coiled element pivotally secured in the bottom rail of said sash, a transverse member secured in the middle portion of said frame, a bearing for the upper end of said coiled element, 90 a flange on said projection, adapted to engage the inner surface of said coiled element secured to said transverse member, a projection on the bottom rail of said sash, that enters the spiral groove in said coiled element, and handle means secured to said transverse member, operatively connected with said worm, for turning the latter to raise and lower said sash.

2. In a device of the type described, the combination with a frame, of a sash vertically movable in said frame, a spirally coiled element pivotally secured in the bottom rail of said sash, a transverse member secured in the middle portion of said frame, 100 a stud projecting outwardly from the bottom rail of said sash, a roller on said stud adapted to loosely enter the spiral slot formed by said coil, a flange on said roller, adapted to engage the inner surface of said coil, and handle means secured to said transverse member, operatively connected with said coiled element, for turning the latter to raise and lower said sash.

3. In a device of the type described, the combination with a frame, a lock board secured to the middle portion of said frame, a fence iron projecting above the top inner edge of said board, of a sash vertically movable in said frame, a bottom rail on said 120 sash, a flange on said bottom rail, a worm for raising said sash, having its spiral groove enlarged at the top, and a boss carried by the bottom rail of the sash, adapted to be engaged by the upper curved wall of the 125 130

- enlarged portion of the worm's spiral groove, to shift the bottom rail of the sash a sufficient distance toward the lock board to hook said flange over the fence iron, for the purpose specified.
4. In a device of the type described, the combination with a frame, a lock board secured to the middle portion of said frame, a fence iron projecting above the top inner edge of said board, of a sash vertically movable in said frame, a bottom rail on said sash, a flange on said bottom rail, a vertical worm, means for turning said worm, a flanged roller pivotally secured to said bottom rail, adapted to travel in the spiral slot in said worm, said slot being enlarged at the top of said worm to release the flanged roller, and a beveled boss secured to said supporting member, adapted to be engaged by the curved upper edge of the metal strip around the enlarged portion of said slot, to shift the bottom rail of the sash a sufficient distance toward the lock board to hook said flange over the fence iron, for the purpose specified.
- 10 5. In a device of the type described, the combination with a frame, a lock board secured to the middle portion of said frame, a fence iron projecting above the inner edge of said board, of a sash vertically movable in said frame, a bottom rail on said sash, a flange on said bottom rail adapted to hook over said fence rail, a coiled element for lowering said sash, and a flanged projection on said bottom rail coöperating with said coiled element, to automatically disengage said flange from said fence iron when the rotary motion of the coiled element is started to lower the sash.
- 15 6. In a device of the type described, the combination with a frame, a lock board secured to the middle portion of said frame, a fence iron projecting above the inner edge of said board, of a sash vertically movable in said frame, a bottom rail on said sash, a flange on said bottom rail adapted to hook over said fence rail, a coiled element for lowering said sash, and a flanged projection on said bottom rail coöperating with said coiled element, to automatically disengage said flange from said fence iron when the rotary motion of the coiled element is started to lower the sash.
- 20 5. In a device of the type described, the combination with a frame, a lock board secured to the middle portion of said frame, a fence iron projecting above the top inner edge of said board, of a sash vertically movable in said frame, a bottom rail on said sash, a flange on said bottom rail, a vertical worm, means for turning said worm, a supporting member on said bottom rail, a stud
- 25 on said supporting member, a roller on said stud, adapted to travel in the spiral slot in said worm, a flange on said roller wider than said slot and adapted to travel behind the same, said slot being enlarged at the top of said worm to release the flanged roller, and a beveled boss secured to said supporting member, adapted to be engaged by the curved upper edge of the metal strip around the enlarged portion of said slot, to shift the bottom rail of the sash a sufficient distance toward the lock board to hook said flange over the fence iron, for the purpose specified.
- 30 6. In a device of the type described, the combination with a frame, a lock board secured to the middle portion of said frame, a fence iron projecting above the inner edge of said board, of a sash vertically movable in said frame, a bottom rail on said sash, a flange on said bottom rail adapted to hook over said fence rail, a coiled element for lowering said sash, and a flanged projection on said bottom rail coöperating with said coiled element, to automatically disengage said flange from said fence iron when the rotary motion of the coiled element is started to lower the sash.

In testimony whereof I have hereunto set my hand this 23rd day of October, 1920.

OLIVER W. WHITEHEAD.

Witness:

HOWARD S. SMITH.
